UNITED STATES PATENT OFFICE.

CARL LOUIS MAX PREUSS, OF LEIPSIC, GERMANY.

DESIGN FOR AN EASTER-CARD.

SPECIFICATION forming part of Design No. 25,381, dated April 14, 1896.

Application filed August 6, 1895. Serial No. 558,424. Term of patent 3½ years.

To all whom it may concern:

Be it known that I, CARL LOUIS MAX PREUSS, bookkeeper, a subject of the Emperor of Germany, residing at 8 Rudolfstrasse, 5 Leipsic, Kingdom of Saxony, Germany, have invented and produced a new and original Design for Easter-Cards of Congratulation, of which the following is a specification.

In the accompanying drawing the design is 10 represented.

It consists of a square card, having the shape and ornamentation shown in the accompanying drawing, comprising a central

circular figure made up of broken and irregular and broken lines. 15

What I claim is—

The design for an Easter-card as herein shown and described.

In witness whereof I have hereunto signed my name in the presence of two subscribing 20 witnesses.

CARL LOUIS MAX PREUSS.
